INTERNAL COMBUSTION ENGINE

Max Schniekart, Chesaning, Mich.

Application March 1, 1940, Serial No. 321,771

1 Claim. (Cl. 309—15)

My invention relates to improvements in internal combustion engines and more particularly to piston equipment therefor.

The principal object of the invention is to equip an internal combustion engine with a piston assembly whereby side thrust on the piston is reduced to a minimum under operation of the crank shaft and wear on the piston rings and cylinder walls minimized, thereby prolonging the life and efficiency of the engine.

To the accomplishment of the above, and subordinate objects presently appearing, a preferred embodiment of my invention is illustrated in the accompanying drawings, set forth in detail in the succeeding description and defined in the claim appended hereto.

In said drawings:

Figure 1 is a view in vertical section of an internal combustion engine equipped with the preferred embodiment of my invention.

Figure 2 is a view in top plan of the follower,
Figure 3 is a view in bottom plan,

Figure 4 is a view in transverse section taken on the line 4—4 of Figure 2, and

Figure 5 is a similar view taken on the line 5—5 of Figure 2.

Referring to the drawings by numerals, I have shown my invention therein as applied to an internal combustion engine illustrated conventionally, as sufficient to a proper understanding of the invention, 1 designating a cylinder thereof, 2 the cylinder head, 3 the crank case, 4 the crank shaft and 5 the piston of said cylinder. The numeral 6 designates the usual water jacket, 7 an intake valve, 8 part of the intake manifold, 9 the socket for a spark plug, not shown, 10 the guides for the valve tappet rod, not shown, and 11 the piston rings.

According to my invention, the cylinder 1 is longer than the usual cylinder, for a purpose presently seen. A cylindrical piston follower 12 is provided immediately below the piston 5, said follower including a sleeve 13 having a working fit in the cylinder 1 and being of any suitable width. Upstanding from the sleeve 13 in the axis thereof, and of the piston 5, is a stem 14 having a bifurcated lower end 15, within the sleeve 13, connected to the latter by webs 16 extending therefrom in ninety degree angular relation, said end of the stem being apertured, as at 16', to receive a wrist pin 17 suitably secured therein. As will be understood, the sleeve 13, stem 14 and webs 16 are integral. The stem 14 is provided with an enlarged apertured upper end 18 connected to the piston by a pin 19, to

which said end 18 is suitably fixed and which is fixed to the piston 5 diametrically thereof.

The follower 12 and crank shaft 4 are connected by the piston rod 20 secured to the crank shaft 4 in the usual manner as indicated at 21 and having an apertured upper end 22 fitting in the end 15 of stem 14 and through which the wrist pin 17 extends. The axes of the pins 17 and 19 are parallel.

10 The sleeve 13 upon opposite sides of the axis of the wrist pin 19 is formed in quadrant portions 23 which are relatively thicker than the rest of said sleeve to reinforce the sleeve against wear under side thrust caused by throw of the piston rod 20 on the follower.

As will now be clear, under the power stroke of the piston 5, the power is transmitted to the follower 12 in a straight line and the piston is relieved of side thrust wear such as occurs under throw of the piston rod in the usual engine. In effect, the follower 12 acts as a crosshead against which said side thrust is exerted. This obviates piston slap and tendency of the piston and cylinder wall to wear out of round, also wear on the piston rings 11. Reducing wear on the piston rings 11 and cylinder wall provides for maintaining compression and thereby obviating loss of power. The follower 12 is made of light hard metal adapted to withstand prolonged use. The friction between the follower 12 and the wall of the cylinder 2 will not materially affect speed, for the reason that maximum compression is maintained and friction between the rings 11 and cylinder wall is reduced, said rings being prevented from tilting.

If it is not possible to insert the wrist pin 17 from below the member 12 then holes 12' can be formed in the follower to permit the pin 17 to be put in place.

40 The foregoing will, it is believed, suffice to impart a clear understanding of my invention without further explanation.

Manifestly, the invention as described is susceptible of modification without departing from the inventive concept, and right is herein reserved to such modifications as fall within the scope of the subjoined claim.

What I claim is:

50 A piston assembly for internal combustion engines comprising a cylindrical piston member, a cylindrical follower of the same diameter as said piston, and means to connect said piston and follower together in spaced relation comprising a diametrical wrist pin in said piston, a stem integral with said follower and articulated with

said piston extending from said pin out of said piston and having a bifurcated end disposed centrally in the follower, webs extending from opposite edges of the furcations of said ends to the inner wall of said follower substantially radially of the latter, and a wrist pin extending through

5

said furcations diametrically of the follower and intermediate said webs and for connecting a connecting rod to said end of the stem intermediate said furcations.

MAX SCHNIEKART.
